UNITED STATES PATENT OFFICE.

LOUIS W. DOWNES, OF PROVIDENCE, RHODE ISLAND.

FUSE.

1,277,880.

Specification of Letters Patent. Patented Sept. 3, 1918.

Application filed November 23, 1916. Serial No. 132,950.

To all whom it may concern:

Be it known that I, LOUIS W. DOWNES, a citizen of the United States, and resident of the city of Providence, in the county of

5 Providence and State of Rhode Island, have invented certain new and useful Improvements in Fuses, of which the following is a specification.

This invention relates to electric indicating fuses more particularly to those of the cartridge type usually in very small sizes for use in circuits of low potential. Fuses of this type have usually heretofore had tubular bodies of glass and are very delicate 10 and easily broken in handling.

The primary object of my present invention is to provide an indicating fuse of this diminutive size that is strong and durable and capable of withstanding the ordinary 20 use to which such fuses are usually subjected, to accomplish which I have formed the same with a comparatively solid body portion of wood, or other fibrous or non-yielding material having a small longitudinal

25 fuse link carrying hole therethrough, and have provided end caps for this body to which the link is connected. This body is also provided with a transverse sight hole, the ends of which are covered with a transparent material through which the condition of the link may be readily observed.

With these and other objects in view, the invention consists of certain novel features of construction, as will be more fully described, and particularly pointed out in the appended claims.

In the accompanying drawings:

Figure 1— is a central sectional elevation of my improved type of fuse.

40 Fig. 2— is a perspective view showing the solid body portion of the fuse.

Fig. 3— is a central sectional end view through the body portion.

Fig. 4— is a perspective view of a transparent tubular-shaped closure for the ends 45 of the sight hole.

Fig. 5— is a cross section of the body showing the ends of the sight hole as closed by a transparent disk secured in position 50 by the pasting of a label over its edges.

Fig. 6— is a section of the body showing a thin transparent sheet as wound about the body in spiral form to close the ends of the sight hole.

55 Fig. 7— is a view of one form of label which may be arranged to retain the closure

disks in position over the ends of the sight hole.

Fig. 8— is a perspective view of one of the end caps.

The body portion 10 of this fuse may be constructed of wood, fiber or other mechanically strong insulating material which is not brittle. This body portion is provided with a comparatively small longitudinal hole 11 65 extending through it, the diameter of the hole being slightly larger than the wire of the fuse link 12, which extends therethrough. This body portion is also provided with a sight hole 13 of greater 70 diameter than the fuse link hole which cuts through the body portion so as to intersect the small hole substantially midway the length of the body portion. The ends of this body portion 10 are provided with contact caps 14 of brass or other suitable conducting material, which caps are attached to the body portion by pins 15, rivets, screws, indentations or by being crimped thereon or by other suitable means. 75

The ends of this sight hole 13 may be closed by any suitable transparent member or members, such for instance as the transparent tubular section 16 shown in Fig. 4, or the small disks 17 illustrated in Fig. 5, 80 which may be inserted into counter-bored ends of the sight hole 13 as illustrated, or the hole may be closed by a thin transparent sheet 18 shown in Fig. 6, which may be wound in spiral form about the body of the 85 fuse over the ends of the sight hole. All of these closures serve the useful purpose of preventing molten metal, sparks or flame from being thrown out through the sight hole when the link is blown. 90

When the disks 17 are employed for closing the sight hole, they may be retained in position by pasting labels over their edges, or by winding a label 20, see Fig. 7, about the body portion of the fuse, which will be 100 provided with holes 21 at the closures a little smaller in diameter than that of the closing disks, so that the edges of the closing disks will be retained in their counter-sunk openings and yet permit unobstructed 105 sight through the sight hole 13.

These tubes, disks or spiral sheets are preferably constructed of gelatin rendered insoluble in water from an admixture of formaldehyde, or these closures may be constructed of other transparent insulating material not readily destroyed by flame. 110

That portion of the body which is visible through the transparent closures may be stained, dyed or otherwise colored to render its appearance attractive. The inner surface of the transparent hole may be colored white if desired so that the condition of the fusible link may be more easily distinguished and the observer can tell whether or not the link has been blown. This particular type of fuse is more especially designed for use on circuits of low potential, and of relatively small amperage such for instance as the electric lighting systems, ignition systems and starting motor systems for automobiles and the like, and other circuits of very low capacity.

These systems are usually operated on from 6 to 25 volts and, as a rule, the battery which forms the source of energy is capable of delivering approximately but 100 to 500 amperes even when short circuited.

The chief advantages of my improved fuse are: first, it visually indicates the condition of the fuse link; second, it possesses great mechanical strength for a fuse of its very small size; and third, when this fuse is made in the preferred form with the insoluble gelatin closure for the sight hole, it becomes almost proof against breakage or mechanical injury in ordinary handling.

It has been found in practice that when the automobile operator wishes to remove one of these small fuses from its clips or fuse block, he almost invariably uses a screw driver as a lever with which to pry it loose, such rough treatment of the usual form of "glass fuse" frequently breaks and destroys it, then again when this old form of indicating fuse is used which has its indicating wire at or near the surface, this indicator is quite likely to be destroyed by such rough usage, and therefore, to obviate this difficulty, I have provided an indicating fuse with a comparatively solid body which has no readily injured parts, whereby this fuse is possessed of sufficient strength to withstand considerable usage without injury.

It will be readily seen that my improved fuse possesses all of the visually indicating advantages of the so-called "glass fuse" and

exposed wire indicating fuse, and in addition has great injury resisting strength not possessed by any other fuse which is due to the fact that the body portion of my fuse is solid and covered with a transparent material which is semi-flexible, resilient and not easily broken, which construction enables it to withstand much mechanical abuse before it becomes injured to such an extent that it will not continue to perform its normal function.

I have described one illustrative embodiment of my invention, but the details of this construction may be varied without departing from the spirit of my invention, the scope of which is defined and limited only by the appended claims.

I claim:

1. An electric fuse comprising a body portion of fibrous material having a comparatively small longitudinal bore therethrough, end caps of conducting material fitted over said body and closing the ends of said bore, a fusible link extending through said bore and connected to said caps, the diameter of said bore being a little larger than that of said link, said body being provided with a transverse sight hole therethrough, and a transparent closure for the ends of said sight hole.

2. An electric fuse comprising a body portion of tough non-yielding material having a comparatively small hollow longitudinal bore therethrough, caps of conducting material on the ends of said body closing the ends of said bore, a fusible link extending through said bore and connected to said caps, the diameter of said bore being a little greater than that of said link, said body being provided with a transverse sight hole, a closure of semi-flexible transparent material fitted to cover the ends of said sight hole, and means for securing said closure in position.

In testimony whereof I affix my signature in presence of two witnesses.

LOUIS W. DOWNES.
